UNITED STATES PATENT OFFICE.

HAROLD C. ROOD, OF BRIDGEPORT, CONNECTICUT.

MAN'S GARTER.

1,270,057.

Specification of Letters Patent. Patented June 18, 1918.

Application filed March 18, 1918. Serial No. 223,066.

To all whom it may concern:

Be it known that I, HAROLD C. Rood, a citizen of the United States, and resident of Bridgeport, in the county of Fairfield and

5 State of Connecticut, have invented certain new and useful Improvements in Men's Garters, of which the following is a specification.

My invention relates to new and useful 10 improvements in men's garters such as are designed to encircle the leg and provided with depending means for engaging and supporting a hose.

The object of the invention is to provide 15 a simple and inexpensive form of that class of garter employing a closed leg embracing webbing, and to design a garter that can be made up with very few trimmings and connected parts, so as to be durable and well 20 serve to properly support the hose. The invention belongs to that particular type of garter which includes a relatively large elastic leg encircling band, the ends of which are united to form a closed band and to 25 which the tab for supporting the clasp is attached, and known to the trade as a "slip on" garter.

With these and other objects in view the invention resides and consists in the construction and novel combination and arrangement of parts hereinafter more fully described, illustrated in the accompanying drawings, and pointed out in the claims here-to appended, it being understood that various changes in the form, proportion, size and minor details of construction within the scope of the claims may be resorted to without departure from the spirit or sacrificing any of the advantages of the invention.

40 Similar characters of reference denote like or corresponding parts throughout the several figures of the accompanying drawings forming a part of the specification, and upon which,

45 Figure 1 shows a front perspective view of my improved form of men's garter.

Fig. 2 is a front elevation of the front portion of the garter, minus the finishing strip, which is shown separately in Fig. 5.

50 Fig. 3 is a side edge view of the clasp and its supporting tape, ready for attachment to the adjoining ends of the elastic webbing, as shown in Fig. 2.

Fig. 4 is a central vertical sectional view 55 taken on line 4—4 of Fig. 1, and

Fig. 5 is a plan view of the finishing strip employed for covering the adjoining ends of the leg encircling webbing and the attached end portion of the tape.

Referring in detail to the characters of 60 reference marked upon the drawings, 6 represents the leg encircling band which is formed of relatively wide elastic webbing, and whose end portions are brought together as shown in Figs. 1 and 2 and stitched to the 65 clasp supporting tape 7 by two parallel lines of stitching 8—8 and top and bottom cross stitching 9—9. This tape is thus attached to the inside of the leg encircling webbing for the purpose of carrying the clamping 70 loop 10 and stud 12, which together engage the hose to be supported.

The clamp supporting tape 7, as will be seen from Figs. 3 and 4 is formed of a single strip of material and is suitably folded 75 and threaded through the base 11 of the stud 12, and the loop 10 is indicated, in a manner to support the same in their relative positions. In this connection it will be seen that the main stem of the tape extends down 80 from the webbing and is returned through the base plate 11 of the button 12 and is disposed against the intermediate portion of the tape and then folded to form a loop 13 in which the wire loop 10 is held. The end 85 14 of the tape is disposed against the folded portion of the tape and the three thicknesses are stitched to the straight back portion by a row of stitching 15 as shown in Fig. 3. These parts of the garter including the as- 90 sembled tape, button and loop are in practice assembled to form the unit shown in Fig. 3 and are then stitched to the ends of the webbing in the manner shown in Fig. 2. The covering strip 16 of the non-elastic ma- 95 terial is suitably folded and laid across the adjoining ends of the encircling webbing and the attached end portion of the tape. This strip is secured by two parallel rows of

stitches 17 that are placed along the two side 100 edges of the strip, and a cross row of stitches 18 that is run along the top edge. The two depending ends of this covering strip are disposed downward slightly below the lower edge of the webbing and there stitched together by the row of stitches 19 that pass through the six thicknesses of material including the previously folded portions of the tape which had already been stitched together. This when completed, as will be 105 110

noted, forms a neat appearing garter having no buckles and comprising but three pieces of fabric and two metal parts.

Having thus described my invention, what I claim and desire to secure by Letters Patent, is—

1. A man's garter of the class described, comprising a relatively wide leg band of elastic material, a depending supporting tape attached to one side of the adjoining end portions of said leg band and stitched to the two adjoining ends, the tape being extended downward to support a button and having its lower portion looped to support a clasp and stitched to its intermediate portion, and a finishing strip covering the attached end of the tape and stitched to the end portions of the leg band, the lower end portions of the strip depending below the elastic being stitched to the tape.

2. A man's garter of the class described, comprising a relatively wide leg encircling member of elastic material, a depending

clasp supporting tape covering one side of the adjoining end portions of said leg encircling member and stitched to the respective ends by rows of stitches running along the edge portion of the tape and crosswise of the two adjoining end portions of the leg band, the tape being extended downward to support a clasp and its end portion being stitched to its intermediate portion beneath the leg band, and a finishing strip covering the attached end of the tape and the end portions of the leg encircling members and stitched thereto by parallel rows of stitches, the lower end portions of the strip depending below the elastic being stitched to the loop of the tape.

Signed at Bridgeport in the county of Fairfield and State of Connecticut this 13th day of March, A. D., 1918.

HAROLD C. ROOD.
